UNITED STATES PATENT OFFICE

103,670

DESIGN FOR A TRAY

Martha H. Connor, Baltimore, Md., assignor to Owens-Illinois Can Company, Wilmington, Del., a corporation of Delaware

Application February 1, 1937, Serial No. 67,372

Term of patent 7 years

To all whom it may concern:

Be it known that I, Martha H. Connor, a citizen of the United States, residing at Baltimore in the State of Maryland, have invented a new, original, and ornamental Design for a Tray, of which the following is a specification, reference being had to the accompany drawing forming a part thereof.

In the drawing:

Fig. 1 is a top plan view of a tray showing my new design.

Fig. 2 is a side elevational view thereof.

I claim:

The ornamental design for a tray substantially as shown.

MARTHA H. CONNOR.
